UNITED STATES PATENT OFFICE.

CARL F. HARTKOPF, OF MARION, ILLINOIS, ASSIGNOR OF TWENTY-FOUR ONE-HUNDREDTHS TO A. M. NORMAN AND TWENTY-FOUR ONE-HUNDREDTHS TO P. J. SWAN, BOTH OF MARION, ILLINOIS.

CAR-COUPING.

1,267,217.

Specification of Letters Patent. Patented May 21, 1918.

Application filed April 12, 1916. Serial No. 90,628.

To all whom it may concern:

Be it known that I, CARL F. HARTKOPF, a citizen of the United States, residing at Marion, in the county of Williamson and State 5 of Illinois, have invented certain new and useful Improvements in Car-Couplings; and I do hereby declare the following to be a full, clear, and exact description of the invention, such as will enable others skilled in 10 the art to which it appertains to make and use the same.

The primary object of this invention is to simplify the general construction of car coupler, so as to admit of the knuckle of the 15 same being conveniently and expeditiously locked or unlocked.

Another object of the invention is to provide a novel type of locking device for the knuckle, which is of simple and durable construction and efficient in operation, and so 20 associated with the coupler that it will not be affected by weather conditions.

Other objects will appear and be better understood from that embodiment of my 25 invention of which the following is a specification, reference being had to the accompanying drawings forming a part thereof, in which:

Figure 1 is a plan view of the coupler 30 having the removable portion thereof removed,

Fig. 2 is a transverse section taken through the coupler,

Fig. 3 is a longitudinal sectional view, 35 taken through the same,

Fig. 4 is a transverse section, taken through the coupler and showing the knuckle locking mechanism in released position,

Fig. 5 is a perspective view of the knuckle 40 removed from the coupler,

Fig. 6 is a perspective view of an element of the locking mechanism removed from the coupler, and

Fig. 7 is a perspective view of another 45 element of the operating mechanism removed from the coupler.

Referring to the drawings in detail, the letter A designates the coupler as an entirety, and which is of the Janney type, the 50 said coupler consisting of a body portion formed of a lower section 1 and an upper removable section 2, the said sections being secured together by means of fastening ele-

ments 3. The lower section 1 is provided with a recess 4, which opens into the upper 55 side of the section 1 and the lower wall of the recess 4 has a longitudinal slot 5 therein, which communicates with the recess 4 and the outer surface of the lower wall, and the said lower wall has its inner surface cut-away to provide a central inclined portion 6 and a seat 7, which seat is located at the lower end of the inclined portion 6. The forward wall of the section 1 is provided with an opening 8, which communicates 60 with the recess 4, as shown in Fig. 1 of the drawings.

The knuckle of the coupler is designated by the numeral 9 and has a hub 10 formed thereon, which is received between ears 11 and 12 carried by the respective sections 1 and 2, the hub is pivoted between the ears 11 and 12 by the pivot pin 13. A tail 14 is carried by the knuckle 9 and extends rearwardly and through the opening 8 in the 65 forward wall of the lower section, and into the recess 4 and is adapted to be engaged by suitable locking mechanism, located within the recess, when the knuckle is in operative position.

The locking mechanism consists of a slide- 70 able member 15, which is tapered throughout its length and has the larger end thereof provided with a substantially semicircular recess 16, which receives the inner end of 75 the arm 14. The member 15 is adapted to be held against sliding movement, when the knuckle is in locked position, by means of a locking head 17, which is rotatably mounted within the recess 4 by means of the trun- 80 nions 18, which are carried by the opposite sides of the head 17, and are received by bearing recesses 19 formed in the side walls of the recess 4. The head 17 is positioned at the smaller end of the member 15 and 85 that end of the head 17, which opposes the adjacent end of the member 15, is flat, as shown at 20, and is adapted to engage the adjacent end of the member 15, when the head is in locking position, as shown in Fig. 100 2 of the drawings, so as to prevent sliding movement of the member 15. The opposite end of the head 17 is curved, as shown at 21, to admit of the rotation of the head within the seat 7. An arcuate shaped lever 22 de- 105 pends from the under side of the head 17

and through the slot 5 and provides means for rotating the head 17, and for raising and supporting the member 15 during the sliding movement of the latter.

5 When it is desired to unlock the knuckle 9, the lever 22 is operated so as to move the convex side thereof into engagement with the lower side of the movable member 15 and raise the member. During the movement of the lever the head 17 is rotated and movement of the lever is continued until the lever abuts the opposite end wall of the slot 5, so as to limit the movement of the lever. When the lever comes into contact with the 15 said end wall of the slot 5 the head 17 will have been rotated sufficiently to cause the flat end 20 thereof to aline with the under side of the movable member 15 so that when outward pull is exerted on the knuckle, the 20 arm 14 will slide the member 15 onto the head 16, as shown in dotted line position in Fig. 4 of the drawings. When the knuckle has been uncoupled and returned to normal position the member 15 will gravitate and 25 slide back to normal position, and the lever 21 will return to normal position and rotate the head 17 in the opposite direction, so as to present the flat end 20 of the head 17 to the adjacent end of the member 15, so as to prevent sliding of the member 15.

The opposite side walls of the recess 4 are provided with grooves 23, which consist of a lower horizontal portion and an upper inclined portion, which extends to the upper 35 edge of the lower section 1. The bearings or recesses 19 are formed in the lower walls of the horizontal portions of the grooves. The grooves 23 provide means whereby the head 17 can be conveniently removed and 40 replaced within section 1. The section 1 has its inner surface provided with a recess 24, so as to provide a clearance for the member 15, when the latter is being moved onto the head 16.

Copies of this patent may be obtained for five cents each, by addressing the "Commissioner of Patents, Washington, D. C."

What is claimed is:

1. A car coupler comprising a head having a recess therein, a knuckle pivotally associated with the head, a tail carried by the knuckle and extending into the recess, a member pivoted directly to the tail, a locking element pivoted within the recess and adapted to engage the member to lock the knuckle, and a manipulating element carried by the locking member, said manipulating member being adapted to move the locking member to locking position.

2. A car coupler comprising a head formed of a lower section and an upper removable section, the lower section having a recess therein, the opposite side walls of the recess having grooves therein including a horizontal portion and an upwardly inclined portion, said inclined portion extending to the upper edge of the lower section, the lower walls of the horizontal portions of the grooves being provided with semi-circular depressions, a knuckle pivotally associated with the head, a tail carried by the knuckle and extending into the recess in the lower section, a movable member located within the recess in the lower section and connected directly to the tail, a locking element for engaging behind the member located within the recess when the latter is in a lowered position for normally holding the member against movement and having trunnions thereon rotatably received in the depressions formed in the lower walls of the horizontal portions of the grooves, said grooves forming means whereby the locking element can be conveniently removed from the lower section, as and for the purpose specified.

In testimony whereof I affix my signature in presence of two witnesses.

CARL F. HARTKOPF.
